Term of patent 14 years

(Cl. D34—5)

FIG. 2

FIG. 3

FIG. 1 is a front or face view of a golf club head embodying my new design;

FIG. 2 is an elevation view of the head as seen from the right-hand end of the head as shown in FIG. 1; and

FIG. 3 is a sectional view taken substantially along the line 3—3 in FIG. 1.

The broken lines indicating a portion of a shaft in FIG. 1 are for illustrative purposes only.

I claim:

The ornamental design for a golf club head, as shown and described.
